[57] CLAIM

The ornamental design for a combined set of unitary wire handles/legs for a chafing stand, as shown and described.

DESCRIPTION

FIG. 1 is a top front right side perspective view of a combined set of unitary wire handles/legs for a chafing stand showing my new design;

FIG. 2 is a top plan view of the right handle/leg, the left handle/leg removed for ease of illustration and being identical to the right;

FIG. 3 is a front elevational view thereof;

FIG. 4 is a rear elevational view thereof;

FIG. 5 is a right side elevational view thereof; and,

FIG. 6 is a bottom plan view thereof;

The broken lines in FIG. 1 are for illustrative purposes only and forms no part of the claimed design.

1 Claim, 3 Drawing Sheets

FIG. 2

FIG. 3
